UNITED STATES PATENT OFFICE.

JOSÉ LOMBARDERO, OF SAN FRANCISCO, CALIFORNIA.

SMOKER'S KIT.

1,135,457.

Specification of Letters Patent. Patented Apr. 13, 1915.

Application filed July 22, 1913. Serial No. 780,536.

To all whom it may concern:

Be it known that I, JOSÉ LOMBARDERO, a citizen of the United States, residing at San Francisco, in the county of San Francisco and State of California, have invented new and useful Improvements in Smokers' Kits, of which the following is a specification.

The invention relates to a combination smoker's kit, and more especially to a combined tobacco box, cigarette former, lighter and cigarette paper holder.

The primary object of the invention is the provision of a device of this character wherein tobacco can be conveniently carried, a cigarette rolled, the tobacco being fed into the former in a novel manner, and also which will afford a lighter.

Another object of the invention is the provision of a device of this character wherein the cigarette former can be readily manipulated for the making of a cigarette from the tobacco within the box, the device being neat and attractive in appearance, and also which is compact in form so that it can be carried by the user.

A further object of the invention is the provision of a device of this character which is simple in construction, reliable and efficient in operation, and inexpensive in manufacture.

With these and other objects in view, the invention consists in the construction, combination and arrangement of parts as will be hereinafter more fully described, illustrated in the accompanying drawing, and pointed out in the claims hereunto appended.

In the drawings: Figure 1 is a front elevation of a device constructed in accordance with the invention. Fig. 2 is an edge elevation thereof. Fig. 3 is a top plan view. Fig. 4 is a bottom plan view. Fig. 5 is a view similar to Fig. 3, showing the lid open. Fig. 6 is a view similar to Fig. 4, showing the door at the bottom open. Fig. 7 is a vertical longitudinal sectional view through the box. Fig. 8 is a perspective view of the cigarette former removed. Fig. 9 is a perspective view of the plunger used with the former. Fig. 10 is a sectional view on the line 10—10 of Fig. 1.

Similar reference characters indicate corresponding parts throughout the several views in the drawings.

Referring to the drawings in detail, A designates a box-like body forming a container for tobacco having a lid B at its top

which is normally held closed through the medium of a spring C, the said lid being suitably hinged to the body and is provided with a latch tongue D provided with a suitable snap fastener E whereby the same may be locked for sustaining the lid fast when closed. The bottom of the body A is provided with a hinged door F which is fastened in closed position in any suitable manner and permits communication with a chamber G formed by a division line or partition H so that access may be had to a lighter presently described. The body A is formed with rounded longitudinal edges 10, 65 70 and mounted interiorly thereof and supported by one of its flat walls is a receptacle 11 for receiving cigarette papers, while one rounded edge 10 is provided with a channel 12 extending only partially of the length of 75 the box and in which is held a cigarette former presently described.

The lighter comprises a tube-like wick lamp 13, the same being passed through a suitable aperture formed in the wall or partition H and fastened thereto in any suitable manner so that its wick will project into the chamber G, while arranged within the latter at one side of the lamp 13 is an ignition wheel 14, a portion of its perimeter projecting through a slot 15 in one side wall of the body H exteriorly thereof whereby it may be manually rotated, the wheel 14 being designed to work against a carborundum stick 16 held within a sleeve 17 secured to one 80 side wall of the body and projected into the chamber G. Threaded in the sleeve and projected exteriorly of the body is an adjustable feed screw 18 which acts upon a spring 19 which is held within the sleeve 85 17, the said spring being designed to force the carborundum stick 16 against the perimeter of the wheel 14 so that when rotating the latter a spark will be created and directed to the wick of the lamp 13 for igniting the same. The door F is open so that when the wick 13 of the lamp is lighted a cigarette, cigar, pipe or the like can be lighted.

The cigarette former comprises a forming tube 20 which is located within the channel 12 and is suitably rotatably connected to the bottom of the body A, both ends of the tube being projected beyond the top when closed and the bottom of the body, the end 110 projected beyond the bottom of the body being formed with threads 21 for the de-

tachable engagement therewith of companion threads 22 provided on a plunger 23 which is adapted to be inserted in the said tube 20 and is held therein when not in use.

5 Provided near the threaded end of the tube 20 is an opening 24 which is adapted for communication with the body A so that tobacco can be delivered therefrom into the tube when desiring to form a cigarette. Ex-
10 tending longitudinally of the tube 20 from the opening 24 to the opposite end of the said tube is a slot 25 into which is adapted to be inserted a cigarette paper so that the same can be rolled about the tube 20 when it is
15 rotated for the formation of a wrapper when in the act of making a cigarette. The plunger 23 at its threaded end is formed with a head 26 and on detaching the said plunger from the tube 20 the latter can be
20 filled with tobacco, this being done subsequent to the rolling of the said wrapper about the said tube 20, and thereafter the plunger 23 is inserted in the tube 20 for packing the tobacco in the wrapper as the
25 same is slipped from the tube at the open end thereof, the lid B being provided with a cut-away portion 27 corresponding to the channel 12 so as not to interfere with the removal of the wrapper from the tube when
30 a cigarette is being formed.

From the foregoing it is thought that the construction and manner of operation of the device will be clearly understood, and therefore a more extended explanation
35 has been omitted.

What is claimed is:

1. A smoker's kit comprising a box-like body forming a tobacco receiver, one wall of the body being cut and inwardly bent for a portion of its length to form a channeled opening through one end of the body, a cigarette former removably fitted within the channel and having an opening therein, the said body being formed with an opening communicating with the channel and adapted for alignment with the opening in the cigarette former, and a plunger detachably mounted within the said former.

2. A smoker's kit comprising a box-like body forming a tobacco receiver, one wall of the body being cut and inwardly bent for a portion of its length to form a channeled opening through one end of the body, a cigarette former removably fitted within the channel and having an opening therein, the said body being formed with an opening communicating with the channel and adapted for alignment with the opening in the cigarette former, and a plunger detachably mounted within the said former, the said cigarette former being longitudinally slotted from the opening through the opposite open end thereof.

In testimony whereof I affix my signature in presence of two witnesses.

JOSE LOMBARDERO.
